DOOR CONTROL

Hill Bowden, Raleigh, Ga.

Application August 26, 1954, Serial No. 452,236

6 Claims. (Cl. 16—66)

This invention relates to a door control and more specifically provides a device for controlling a movable door during the opening and closing movement thereof in order to prevent the door from hitting the door frame with a violent damaging impact.

An object of this invention is to provide a door closing apparatus that initially resists outward movement of the door and resists inward movement of the door during closing thereof, thereby preventing slamming of the door and positioning the door in its normally closed position.

Another object of the present invention is to provide a door closer having a detachable connection wherein the door will move freely during portions of its movement and will be retarded during other portions of its movement.

Still a further object of the present invention is to provide a door closer having means for adjusting the resistance to movement of the door and yet permitting relatively normal operation of the door.

Other important objects of the present invention reside in its simplicity of construction, ease and efficiency in use, easy installation, its adaptability for its various purposes, and its inexpensive manufacture.

These, together with other objects and advantages which will become subsequently apparent, reside in the details of construction and operation as more fully hereinafter described and claimed, reference being had to the accompanying drawing forming a part hereof, wherein like numerals refer to like parts throughout, and in which:

Figure 1 is a perspective view showing the stationary portion of the door closer in its extended position with the door open;

Figure 2 is a top plan sectional view showing the details of construction of the door closer together with the brackets attached to the door, with the door being in closed position;

Figure 3 is a detail sectional view taken substantially along section line 3—3 of Figure 2, showing the details of construction of the slidable bracket;

Figure 4 is a detail elevational view with portions broken away showing the details of construction of the detachable connection between the bracket and the piston rod; and

Figure 5 is a detail sectional view taken substantially upon a plane passing along section line 5—5 of Figure 2 showing the details of construction of the adjustment valve.

Referring now specifically to the drawing, it will be seen that the numeral 10 generally designates the door closer of the present invention for use in conjunction with an enclosure 12 having a pivotally mounted door 14 therein that is opened and closed during normal use of the device such as a cabinet, house door, or any door on a much-used device.

The door closer 10 includes a generally elongated cylinder 16 having a closed end that is pivotally mounted to a right angular bracket 18 by pivot lugs 20 and pivot

2

pin 22 wherein the right angular bracket 18 is secured to the enclosure 12 by suitable screw fasteners 24. On one side of the cylinder 16 disposed between the cylinder 16 and the bracket 18 is a coil compression spring 24 and 5 on the other side of the pivot pin 22 is an adjustable stop member 26 disposed between the closed end of the cylinder 16 and the bracket 18, thereby permitting limited pivotal movement of the cylinder 16 about pivot pin 22.

Slidably positioned within the cylinder 16 is a piston 10 28 having a sealing ring 30 positioned annularly around the periphery of the piston 28 for engaging the side walls of the cylinder 16, thereby substantially sealing the piston 28 to the cylinder 16. The inner end of the piston 28 in its innermost position contacts an annular shoulder 15 32 which forms an inward limit for the movement of the piston 28. A piston rod 34 is rigidly attached to the outer face of the piston 28 and extends outwardly through an opening 36 in the end of the cylinder 16. A compression spiral coil spring 38 is positioned between the surface of the piston 28 and the end wall of the cylinder 16 in surrounding relation to the piston rod 34 for continuously urging the piston 28 towards the closed end of the cylinder 16. The spiral spring 38 will be collapsed into substantially a cylindrical member with the coils of the spiral being disposed within each other when the piston 28 is moved towards the aperture 36 in the cylinder end wall whereby the spring 38 occupies a very small portion of the space within the cylinder 16.

The piston rod 34 is provided with a pair of oppositely disposed, longitudinally extending projections 40 which slidably engage with grooves 42 in the end wall of the cylinder 16 and a projecting annular flange 44 is formed integrally with the end wall of the cylinder 16 and forms a continuation of the opening 36 in the end wall of the cylinder 16. The outer end of the peripheral flange 44 is provided with inclined or spiral seats 46 that extend across the outer ends of grooves 42 slidably receiving the longitudinal projections 40 and terminate at shoulders formed by faces 43 extending radially thereof. Projections 40 preclude rotational movement of the piston rod until such time as the inner ends of the longitudinal projections 40 move outwardly through the grooves 42 and again engage and ride up the inclined seats 46 on the outer end of the peripheral flange 44.

The inner end of the cylinder 16 is provided with an upstanding lug 48 on the upper surface thereof having an aperture 50 therein and a screw threaded valve member 52 having a tapered groove 54 therein for adjusting the inlet and discharge of air into the interior of the cylinder 16 during movement of the piston 28, thereby retarding and controlling the motion of the piston 28 by adjusting the slot 54 in relation to the passage 50, and controlling the passage of air through the opening 50 into and out of the cylinder 16 in an obvious manner.

Secured to the movable door member 14 is a bracket 56 having inturned edges 58 forming a channel shape for slidably receiving a plate 60 having two projecting arms 62 thereon with a transverse bar 64 interconnecting the outer ends of the arms 62. A generally U-shaped spring member 66 is disposed alongside the plate 60 for urging the plate 60 toward one side of the bracket 56 and the U-shaped spring 66 is provided with a looped central portion 68 which enhances the resiliency of the spring 66. One leg of the U-shaped spring 66 engages the edge of the bracket 56 and the other leg of the U-shaped spring 66 engages the side edge of the plate 60, thereby urging the plate 60 toward the outer edge or free edge of the door 14 and the outer edge of the bracket 56.

The outer end of the piston rod 34 is provided with a transverse spiral slot 70 extending inwardly from the outer end thereof and being substantially the same thick-

ness as the transverse bar 64 for engagement with the bar for detachable interlocking connection between the bar 64 and the piston rod 34, thereby interlocking in a detachable manner the bracket 56 and the piston 28 whereby the initial opening movement of the door 14 and the final closing movement of the door 14 will be controlled by the door closer 10.

In operation, the transverse bar 64 is engaged in the spiral slot 70 substantially as shown in Figure 2 wherein the door 14 is in closed position. Upon outward movement of the door 14, the piston rod 34, together with the piston 28 will be moved outwardly and prevented from rotating by the longitudinal projections 40 riding in the longitudinal grooves 42. As soon as the longitudinal projections pass through the grooves 42, the inner ends of the longitudinal projections 40 will ride up the inclined seats 46 on the peripheral flange 44 inasmuch as the spiral groove 70 engaging the transverse bar 64 will rotate piston rod 34 together with the piston 28 a limited amount until the transverse bar 64 is disengaged from the slot 70. The distance between the inner ends of projections 40 and the last loop of spring 38 is less than the length of flange 44 at the terminal edges of seats 46 whereby the final outward movement of piston rod 34 will be limited by compression of said spring during rotation of the piston rod in one direction due to engagement of the ends of the projections 40 with the inclined seats 46, and the shoulders 43 will limit rotation of rod 34 in the other direction. After the bar 64 is disengaged, the door 14 may be pivoted either way without resistance and upon reclosing of the door 14, the transverse bar 64 will engage the slot 70 which has remained in the same position, and inasmuch as the slot 70 is spiral and the bar 64 engages the edges thereof, the piston rod 34 will again be rotated for aligning the longitudinal projections 40 with the grooves 42, thereby permitting the spring 38 to urge the piston 28 inwardly of the cylinder 16, and cushioning the final closure of the door 14. The limited pivotal movement of the cylinder 16 permitted by the spring 24 and the stop member 26 together with the limited sliding movement of the plate 60 permitted by the spring 66 will retain the detachable connection between the plate 60 and the piston rod 34 in correctly orientated position. Obviously, the device may be constructed of any suitable material and used in any particular use requiring a device of this character.

The device of the present invention is especially useful in controlling the noise and vibrations of a closing door as well as preventing injuries such as broken fingers. Also, the device may be used on refrigerators and other similar enclosed devices in order to prevent accidental captivity of persons in such devices.

From the foregoing, the construction and operation of the device will be readily understood, and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A door closer comprising a stationary cylinder, a piston slidably mounted in said cylinder, a piston rod extending outwardly through one end of said cylinder, a bracket mounted on a movable member, means detachably interconnecting the outwardly extending end of said piston rod and said bracket for retarding the movement of said movable member, said interconnecting means including a spiral slot in the outwardly extending end of said piston rod and a transverse bar mounted on said bracket and positioned in said slot when said movable member is in a predetermined position whereby the piston will be drawn outwardly when the movable member is displaced from said predetermined position, and

means for permitting rotary motion of said piston rod when in its outermost position.

2. A door closer comprising a stationary cylinder, a piston slidably mounted in said cylinder, a piston rod extending outwardly through one end of said cylinder, a bracket mounted on a movable member, means detachably interconnecting the outwardly extending end of said piston rod and said bracket for retarding the movement of said movable member, said interconnecting means including a spiral slot in the outwardly extending end of said piston rod and a transverse bar mounted on said bracket and positioned in said slot when said movable member is in a predetermined position whereby the piston will be drawn outwardly when the movable member is displaced from said predetermined position, and means for permitting rotary motion of said piston rod when in its outermost position, said means for permitting rotation including oppositely disposed longitudinal projections on said piston rod, oppositely disposed grooves in said one end of said cylinder slidably receiving said projections, a pair of spiral seats extending from the outer ends of said grooves for permitting limited rotation of said piston, thereby permitting said bracket and piston rod to be disconnected, said seats retaining said piston rod in extended and orientated position for receiving the bar in the spiral slot when the bracket and piston rod are moved toward each other.

3. A door closer comprising a stationary cylinder, a piston slidably mounted in said cylinder, a piston rod extending outwardly through one end of said cylinder, a bracket mounted on a movable member, means detachably interconnecting the outwardly extending end of said piston rod and said bracket for retarding the movement of said movable member, said interconnecting means including a spiral slot in the outwardly extending end of said piston rod and a transverse bar mounted on said bracket and positioned in said slot when said movable member is in a predetermined position whereby the piston will be drawn outwardly when the movable member is displaced from said predetermined position, means for permitting rotary motion of said piston rod when in its outermost position, and a compression coil spring positioned between the piston and the end of the cylinder in surrounding relation to the piston rod for urging the piston inwardly.

4. A door closer comprising a stationary cylinder, a piston slidably mounted in said cylinder, a piston rod extending outwardly through one end of said cylinder, a bracket mounted on a movable member, means detachably interconnecting the outwardly extending end of said piston rod and said bracket for retarding the movement of said movable member, said interconnecting means including a spiral slot in the outwardly extending end of said piston rod and a transverse bar mounted on said bracket and positioned in said slot when said movable member is in a predetermined position whereby the piston will be drawn outwardly when the movable member is displaced from said predetermined position, means for permitting rotary motion of said piston rod when in its outermost position, and an adjustable valve for permitting controlled passage of air into and out of the cylinder, thereby cushioning the movement of said piston.

5. A door closer comprising a stationary cylinder, a piston slidably mounted in said cylinder, a piston rod extending outwardly through one end of said cylinder, a bracket mounted on a movable member, means detachably interconnecting the outwardly extending end of said piston rod and said bracket for retarding the movement of said movable member, said interconnecting means including a spiral slot in the outwardly extending end of said piston rod and a transverse bar mounted on said bracket and positioned in said slot when said movable member is in a predetermined position whereby the piston will be drawn outwardly when the movable member is displaced from said predetermined position, means for

permitting rotary motion of said piston rod when in its outermost position, and an adjustable valve for permitting controlled passage of air into and out of the cylinder, thereby cushioning the movement of said piston, said means for permitting rotation including oppositely disposed longitudinal projections on said piston rod, oppositely disposed grooves in said one end of said cylinder slidably receiving said projections, a pair of spiral seats extending from the outer ends of said grooves for permitting limited rotation of said piston, thereby permitting said bracket and piston rod to be disconnected, said seats retaining said piston rod in extended and orientated position for receiving the bar in the spiral slot when the bracket and piston rod are moved toward each other.

6. A control for a pair of relatively movable members comprising a cylinder attached to one of said members, a piston slidably mounted in said cylinder, a piston rod extending longitudinally through one end of said cylinder and rigid with said piston, a bracket mounted on the other of said members, means detachably interconnecting the outer end of said piston rod and said bracket for regulating the rate of movement during a portion of the relative movement therebetween, said interconnecting means including a transverse spiral slot in the outer end of the piston rod and a transverse bar on said bracket and positioned in the bottom of said slot when said mem-

bers are in a predetermined relative position, means interconnecting the piston rod and cylinder to prevent rotation thereof during movement of the piston in the cylinder thus locking the bar in the bottom of the slot whereby the piston will be drawn outwardly when the members are initially moved relatively to its outermost position wherein the interconnecting means for said piston rod and cylinder is rendered ineffective, and means permitting rotary motion of said piston rod when in its outermost position thereby permitting engagement and disengagement of said bar and slot, the withdrawal of said bar from said slot during further relative movement of said members causing rotation of the piston rod about its longitudinal axis when the means permitting rotary motion is effective thus rendering ineffective the means interconnecting the piston rod and cylinder.
